CLAIM

The ornamental design for a vacuum regulator with meter assembly used in gas feed systems, as shown and described.

DESCRIPTION

FIG. 1 is a right side view of a vacuum regulator with meter assembly used in gas feed systems showing our new design, wherein the vacuum regulator with meter assembly used in gas feed systems comprises an inlet valve, a pressure relief valve, a yoke assembly;

FIG. 2 is a front view thereof;

FIG. 3 is a right side view of an embodiment of the design of FIG. 1, wherein the vacuum regulator with meter assembly used in gas feed systems further includes an out of gas switch;

FIG. 4 is a front view of the design of FIG. 3;

FIG. 5 is a left rear view of the design of FIG. 1;

FIG. 6 is a right rear view of the design of FIG. 1, wherein the yoke assembly is removed to disclose details not otherwise discernible from the assembled article;

FIG. 7 is a left rear view of the design of FIG. 3;

FIG. 8 is a right rear view of the design of FIG. 3, wherein the yoke assembly is removed to disclose details not otherwise discernible from the assembled article;

FIG. 9 is a left front view of the design of FIG. 1;

FIG. 10 is a left front view of the design of FIG. 3; and,

FIG. 11 is a left rear view of the design of FIG. 3.

The broken lines in the drawings depict portions of the vacuum regulator with meter assembly used in gas feed systems that form no part of the claimed design.
